UNITED STATES PATENT OFFICE

GEORGE H. BENNETT, OF POTEAU, OKLAHOMA

TRANSMISSION

Application filed December 7, 1929. Serial No. 412,531.

This invention relates to transmissions and more particularly to devices of this character which dispense with the use of gears such as are commonly used for transmitting power 5 from one shaft to another.

An important feature of the invention resides in the provision of a rotatable cam disc or plate which co-acts with an oscillating bar mounted in a suitable casing which bar is 10 operatively connected to a crank shaft in a manner to rotate the latter when the bar is oscillated by the cam disc.

Other objects of the invention are to provide, in a manner as hereinafter set forth, a 15 transmission of the aforementioned character which will be simple in construction, positive and silent in operation, strong, durable, and which may be manufactured at low cost.

The foregoing and other objects and advantages of the invention will be more apparent from a study of the following specification, taken in connection with the accompanying drawings wherein like characters of reference designate corresponding parts 25 throughout the several views, and wherein:—

Figure 1 is a longitudinal vertical sectional view of a transmission constructed in accordance with this invention.

Figure 2 is a vertical cross sectional view 30 taken substantially at right angles to Figure 1.

Figure 3 is a horizontal sectional view taken substantially on the line 3—3 of Figure 1 and looking in the direction of the arrows.

Figure 4 is a detail view in top plan, partly 35 in section, showing the oscillating rod which is actuated by the cam disc.

Referring to the drawings in detail, the reference character 1 designates a casing including the convex side walls or body portion 2, a dome 3 on the upper end thereof in communication therewith, said dome being open at its top and provided with a removable closure plate 4 which is secured in place 45 through the medium of the bolts or screws 5.

The lower end of the casing includes a flat bottom wall 6 provided with the centrally disposed opening 7 through which extends the rotatable drive shaft 8 from a suitable source 50 of power. A cam disc 9 is fixed on the inner

end of the shaft 8, as clearly seen in Figure 1 of the drawings. An internally threaded flange 10 extends downwardly from the bottom wall 6 of the casing concentrically with respect to the opening 7 and shaft 8 and constitutes a support or a thrust bearing 11 of any suitable construction.

On diametrically opposite sides, the body portion 2 of the casing 1 is provided with inwardly converging pairs of vertically disposed ribs or flanges 12 which provide dovetail channels 13.

An elongated bar 14 extends transversely over the upper face of the cam disc 9 and is provided, adjacent its opposite ends, with 65 pockets or depressions 15 for the reception of the anti-friction balls 16 which are adapted to travel over the upper face of said cam shaft. On its opposite end, the bar 14 is provided with the cap 17 having the longitudinally extending trunnions 18 which project into the channels 13 of the casing and have mounted thereon the tapered anti-friction rollers 19 which are enclosed in the cages 20, the cages 20 are of a size and configuration 70 to fit slidably between the ribs or flanges 12 in a manner to permit the adjacent end of the bar 14 to move in a vertical plane, said ribs or flanges constituting guides for the opposite end of said bar, as will be apparent.

The upper side of the bar 14 is provided with longitudinally spaced depressions 21 for the reception of the ball heads 22 on the lower ends of the connecting rods 23. The connecting rods 23 are coupled to the bar 14 through the medium of the detachable annular plate or ring 24 which encircles the ball heads 22 and maintain the same in the depressions 21 of the bar. A crank shaft 25 is journaled in the dome portion 3 of the casing, as at 26. The portion of the crank shaft within the dome 3 is provided with a pair of oppositely extending cranks 27 and 28 to which the upper ends of the connecting rods 23 are connected through the medium of universal joints 29. A central main bearing 30 in the form of a universal joint may be provided for the crank shaft between the crank portions 27 and 28 and said main bearing may be 100

supported from the casing in any suitable manner.

In the operation of the transmission, the drive shaft 8 is rotated and like movement is imparted to the cam disc 9 mounted thereon in the casing 1. Rotation of the cam disc 9 will impart oscillatory movement to the opposite ends of the bar 14. As will be obvious, as one end of the bar moves upwardly, 10 the opposite end will be moved downwardly and reciprocatory movement will thus be imparted to the connecting rod 23 with the result that the cranks 27 and 28 will be actuated to rotate the crank shaft 25. The 15 trunnion or projection 18 extending between the guide ribs or flanges 12 prevents the bar 14 from rotating with the cam disc 9 and the anti-friction balls 16 reduce the friction between said bar 14 and the cam disc to a 20 minimum. The cages 20 which are mounted on the trunnion 18 through the medium of the tapered roller bearings 19 also reduce frictional resistance with the guide ribs 12 to a minimum.

25 It is believed that the many advantages of a transmission constructed in accordance with this invention will be readily understood, and although the preferred embodiment of the invention is as illustrated and described, it 30 is to be understood that changes in the details of construction may be had which will fall within the scope of the invention as claimed.

What is claimed is:—

35 1. A transmission of the character described comprising a casing, a drive shaft rotatably extending thereto, a cam disc fixed on the drive shaft, a transversely extending bar mounted for oscillatory movement in the casing and engaged with the cam disc for actuation thereby, a crank shaft rotatably mounted in the casing and connecting rods coupling the crank shaft to the oscillating bar at longitudinally spaced points 40 thereof in a manner to rotate the crank shaft when the bar is actuated.

2. A transmission of the character described comprising a casing, a drive shaft rotatably extending into the casing, a cam disc fixed on the inner end of the drive shaft, an elongated bar mounted for oscillatory movement in the casing and extending transversely across the free face of the cam disc in a manner to be actuated thereby, anti-friction balls disposed between the bar and the cam disc, pairs of vertically disposed guide flanges on diametrically opposite sides of the casing, trunnions mounted on the opposite ends of the oscillating bar and extending between the guide flanges, a crank shaft extending through the casing in vertically spaced relation with respect to the oscillating bar and connecting rods coupling the crank shaft to the bar at longitudinally

spaced points thereof in a manner to rotate the crank shaft when the bar is oscillated.

3. A transmission of the character described comprising a casing, a drive shaft rotatably extending into said casing, a cam disc fixed on the inner end of the drive shaft, an elongated bar extending transversely over the free face of the cam disc and mounted for oscillatory movement in the casing, said bar adapted to be oscillated by the disc when the latter is rotated, anti-friction balls disposed between the bar and the cam disc, pairs of vertically disposed inwardly converging guide ribs formed in the casing on diametrically opposite sides thereof, caps mounted on the opposite end of the oscillating bar, trunnions extending forwardly from the cap and projecting between the guide ribs, tapered anti-friction elements rotatably mounted on the trunnions and disposed between the guide ribs and adapted to travel longitudinally therebetween, a crank shaft extending through the casing in vertically spaced relation with respect to the oscillating bar and mounted for rotation therein, said crank shaft including a pair of oppositely extending crank portions, connecting rods extending between the crank portions of the crank shaft and the oscillating bar, co-acting ball and socket elements for connecting the rods to the bar at longitudinally spaced points thereon and co-acting ball and socket elements for connecting the opposite end of the connecting rod to the crank shaft in a manner to rotate the same when the bar is oscillated.

In testimony whereof I affix my signature.

GEORGE H. BENNETT.
